Primary Examiner — T. Chase Nelson(74) *Attorney, Agent, or Firm* — Dunlap Bennett & Ludwig PLLC(57) **CLAIM**

The ornamental design for a wedge heel base, as shown and described.

DESCRIPTION

FIG. 1 is a perspective front view of a wedge heel base;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings illustrate portions of the wedge heel base that form no part of the claimed design.

1 Claim, 3 Drawing Sheets(56)
